UNITED STATES PATENT OFFICE.

LOUIS RITTER AND JACOB RITTER, OF NEW YORK, N. Y.

DESIGN FOR A BELT-BUCKLE.

SPECIFICATION forming part of Design No. 32,943, dated July 17, 1900.

Application filed June 22, 1900. Serial No. 21,241. Term of patent 3 $\frac{1}{2}$ years.

To all whom it may concern:

Be it known that we, LOUIS RITTER and JACOB RITTER, citizens of the United States, residing in New York, borough of Manhattan, and State of New York, have invented and produced a new and original Design for Belt-Buckles, of which the following is a specification, reference being had to the accompanying drawing, forming part thereof, and which shows a belt-buckle embodying our new design in front elevation.

As shown in the drawing, the leading or material features of our design consist of horseshoe portions A A', a connecting bar portion B, and a substantially C-shaped center piece C. The horseshoe portions have their curved backs presented outwardly, while the

side legs of the same inclose the ends of the bar portion B, which bears a series of beaded trapezoid-shaped ornaments b. The C-shaped center piece C is provided with foliage-like ornamentation d.

What we claim is—

The design for a belt-buckle, as shown and described.

In testimony that we claim the foregoing as our invention we have signed our names in presence of two subscribing witnesses.

LOUIS RITTER.
JACOB RITTER.

Witnesses:

PAUL GOEPEL,
GEO. L. WHEELOCK.
